By Geo. P. Kimmel Attorney

UNITED STATES PATENT OFFICE.

HENRY A. HARRISON, OF NORHEIM, MONTANA.

MAIL-BAG RECEIVER FOR RAILWAY-COACHES.

1,242,437.

Specification of Letters Patent.

Patented Oct. 9, 1917.

Application filed February 26, 1917. Serial No. 150,988.

To all whom it may concern:

Be it known that I, HENRY A. HARRISON, a citizen of the United States, and resident of Norheim, in the county of Blaine and 5 State of Montana, have invented certain new and useful Improvements in Mail-Bag Receivers for Railway-Coaches, of which the following is a specification.

The present invention has reference, generally, to railway appliances; and, the invention relates more particularly to an improved mail bag receiving apparatus.

The invention has for its principal object to provide mail bag receiving apparatus 15 adapted for use on railway mail coaches, whereby, the mail bags will be received thereby and then automatically dropped or delivered into the coach to be emptied and assorted.

20 It is a more specific object of the invention to provide novel mail bag receiving means arranged upon the top or roof of the coach, the same being normally held in position to receive mail bags from a delivering apparatus, in order that the same will be 25 operated by the weight of the bags as deposited thereon to allow the discharging thereof to the interior of the mail coach.

Another object of the invention is to provide yieldable means for normally holding the mail bag receiving means in operative 30 position to permit the passage of mail bags from the delivering means thereinto.

Among other aims and objects of the invention may be recited, the provision of a 35 device of the character mentioned, with a view to compactness, and in which the number of parts are few, the construction simple, the cost of production small, and efficiency 40 and operation high.

In order that the invention and the manner of its application may be readily understood by those skilled in the art, I have in the accompanying illustrative drawings and 45 in the following detailed description based thereon set forth the preferred embodiments of the invention.

In these drawings:

Figure 1 is a fragmentary longitudinal 50 section through a mail coach with my improved mail bag receiving means applied thereto, the bag receiving means being also shown in section and in position to receive bags from the delivering apparatus;

55 Fig. 2 is a front elevation of the receiving apparatus, showing the relative positioning

of the same and the mail bag delivering apparatus; and

Fig. 3 is a fragmentary side elevation of a slightly modified form of bag receiving apparatus.

Similar characters of reference are employed in all of the above described views to indicate corresponding parts.

Referring now more specifically to the 65 several figures of the said drawings, a fragment of a railway mail coach is shown and is designated by the numeral 1, the said coach being provided, as will be understood, with a suitable roof 2 having an opening 3 70 formed therein, the purpose of which will be subsequently apparent.

A mail bag receiving receptacle 4 having an inclined top portion is arranged within the opening 3 as formed in the roof top 2 75 and is pivotally secured thereto through the medium of a pin 5, it being understood that the said pin is secured by suitable fastening devices 6 to the adjacent portions of the mail coach roof and the mail bag receiving 80 receptacle. A depending lug 7 is arranged upon the lower face of the bottom portion of the receiving receptacle 4 and is adapted to be engaged by the upper convolutions of an expandible coiled spring 8, the lower convolutions of which are arranged upon a suitable cross bar or other support 9, certain of the ends of which are secured to one of the side walls of the mail coach 1, as at 10, thus, providing an efficient bracket. To 90 prevent undue lateral movement of the lower convolutions of the spring 8, a lug 11 similar to the depending lug 7 may be and preferably is formed upon said arm or bracket 9 and is adapted to be received 95 within said lower convolutions. As will be noted, the free end of the mail bag receiving receptacle 4 is open and by reason of the expandible coiled springs will be normally maintained in its uppermost position whereby mail bags may be readily passed thereinto.

A pivotal hook 12 is secured to the under face of the inclined top of the receptacle 4 at a point in proximity of the open end thereof and is adapted to be engaged with a suitable eye or staple 13 as arranged upon the under face of the coach roof 2 at a point near the opening 3 therein. By engaging the hook 12 with the eye 13, it will be seen that the receptacle 4 will be 100 held in its lowermost position against the tension of the expandible coiled spring 8. 105 110

When released, however, the receptacle will be immediately forced into its uppermost or opposite position by the said expansible spring 8. To prevent excessive upward movement of the receptacle 4, a laterally extending finger or fingers 8' are arranged upon the marginal edge of the free end of the receptacle bottom and is adapted to engage the adjacent portions of the under face 10 of the car roof 2 when the receptacle is swung into its uppermost or opposite position.

Suitable mail bag delivering means, indicated in its entirety by the numeral 14 is arranged to one side of the rack and is provided with a laterally extending arm 15 on which the mail bag suspending hooks 16 are arranged. It is to be noted, that the suspending hooks 16 are so arranged as to permit the removal of the mail bags when engaged by the receiving apparatus therefrom.

The mail bag 17 when in position upon the suspending hook 16 of the delivering apparatus will be arranged directly in the path of travel of the receiving receptacle 4 as shown in the Fig. 2 and as a consequence, when the said receptacle is moved into engagement therewith, the loops 18 with which the suspending hooks 16 of the delivering apparatus are engaged will be removed from the said suspending hooks and the bag permitted to drop into the receiving receptacle. The weight of the bag 17 upon the bottom of the receptacle 4 is sufficient to cause the yielding of the expansible spring 8 and hence, the tilting of the receptacle bottom 4 whereby to permit the said bag to be discharged into the interior of the coach 1. Upon being relieved of the weight of the bag, it is obvious that the receptacle 4 will be immediately returned to its normal position by means of the expansible coiled spring 8 ready for subsequent operation.

Should it be desired, suitable means may be engaged with the expansible coiled spring 8 whereby to vary the tension of the same so that it will be compressed only upon the depositing of predetermined weights upon the bottom of the receptacle 4. By this means, the bag receiving receptacle may be caused to respond to varying weights.

In Fig. 3 I have shown a slightly modified form of mail bag receiving means 55 wherein a plurality of receiving receptacles 4 are arranged, it being noted, however, that the said receiving receptacles are disposed in opposite directions, whereby mail bags may be collected by the train in an efficient manner when the direction of travel of the same is reversed. In this particular embodiment, it will of course be understood that one of the bag receiving receptacles 4 is permitted to remain in its uppermost or operative position, the remaining

receptacle being secured in inoperative position through the medium of the pivotal hook member 12 which is engaged with its respective eye as arranged upon the coach roof 2. Upon the reversing of the direction of travel of the coach, the positioning of the bag receiving receptacle may be readily reversed.

If desired, the receiving receptacle can be mounted in different positions on the mail coach, such as on the sides of the same; the bag delivering means being positioned to accord with the change.

Obviously, the construction shown is capable of still further modification and such modification as is within the scope of my claims I consider within the spirit of my invention.

I claim:

1. Bag receiving means of the character described, including, in combination with a vehicle movable over a predetermined course, a receptacle movably secured to the top of said vehicle, means for normally maintaining the receptacle in its uppermost position but to allow movement of the same to its lowermost position upon depositing of a bag thereon.

2. Bag receiving means of the character described, including, in combination with a vehicle movable over a predetermined course, a receptacle movably secured to the top of said vehicle, resilient means for normally maintaining the receptacle in its uppermost position but to allow movement of the same upon depositing of a bag therein for discharging the same into the vehicle.

3. Bag receiving means of the character described, including, in combination with a vehicle movable over a predetermined course, a receptacle pivotally secured to the top of said vehicle, spring means engaged with the receptacle for normally maintaining the same in its uppermost positions but to allow movement of the same to its lowermost position upon the depositing of a bag therein.

4. Bag receiving means of the character described, including, in combination with a vehicle movable over a predetermined course and having an opening formed in the roof thereof, a receptacle arranged within said opening and pivotally secured to a portion of the vehicle roof, expansible spring means carried upon a portion of the vehicle and engaged with the receptacle for normally maintaining the same in its uppermost position but to allow movement of the same to its lowermost position upon the depositing of a bag therein, and means carried by the bottom portions of the receptacle engageable with the vehicle roof for preventing excessive upward movement thereof.

5. Bag receiving means of the character described, including, in combination with

a vehicle movable over a predetermined course and having an opening formed in the top thereof, a receptacle arranged in said opening and pivotally secured to a portion of the vehicle roof, spring means carried by the vehicle and engaged with the receptacle for normally maintaining the same in its uppermost position but to allow movement of the same to its lowermost position upon the depositing of a bag therein, means formed integral with the lower portion of the receptacle and engageable with the roof for preventing excessive upward movement of the receptacle, and other means carried upon a top portion of said receptacle

and engageable with the vehicle roof for securing the same in its lowermost position.

6. The combination with a railway car, the roof thereof being provided with a longitudinally extending opening, of a receptacle pivotally secured to the roof of the car adjacent said opening, one end of the receptacle being open to receive articles when the same is exposed above the roof, and fingers formed on the receptacle to limit the upward movement thereof. 20 25

In testimony whereof, I affix my signature hereto.

HENRY A. HARRISON.
